[57] **CLAIM**

The ornamental design for the display-windowed infant-security diaperbag, as shown and described.

DESCRIPTION

FIG. 1 is a front perfective view of the display-windowed infant-security diaperbag showing my new design;
FIG. 2 is a rear perspective view in an open position thereof;
FIG. 3 is a right side elevational view thereof;
FIG. 4 is a left side elevational view thereof;
FIG. 5 is a bottom plan view thereof;
FIG. 6 is a top plan view thereof;
FIG. 7 is a broken away view of the interior panel as shown in FIG. 2 thereof; and,
FIG. 8 is a broken away view of the opposite interior panel of that shown in FIG. 2 thereof.
